UNITED STATES PATENT OFFICE.

FREDERICK W. BROOKS, OF OAK GROVE, WISCONSIN.

CAR-COUPING.

SPECIFICATION forming part of Letters Patent No. 269,257, dated December 19, 1882.

Application filed October 11, 1882. (No model.)

To all whom it may concern:

Be it known that I, FREDERICK W. BROOKS, of Oak Grove, in the county of Dodge, and in the State of Wisconsin, have invented certain new and useful Improvements in Car-Couplings; and I do hereby declare that the following is a full, clear, and exact description thereof.

My invention relates to couplings for railroad-cars; and it consists in certain new and useful improvements on the device embraced in Letters Patent No. 261,301, granted to me July 18, 1882, and will be fully described hereinafter.

15 In the drawings, Figure 1 is a front view of my device. Fig. 2 is a section through line x of Fig. 1, and Fig. 3 is a view of the under side of my improved coupling.

A is the draw-head of my coupling, the shank A of which terminates in spindle a , that carries a spring, a' , and passes through a plate, b , that extends from one of the face-plates b' to the other. These face-plates lie up against beams B B, and to support the front end of the draw-bar I provide a bottom plate, b^2 , that extends across the front ends of beams B B. Shoulders c on the shank of the draw-head work in recesses c' in the face-plates b' , and shoulders c^2 of the latter, by engagement with the shoulders c , limit the longitudinal play of the draw-head.

C is a horizontal sliding frame of general U shape—that is, it has two long arms extending from a short cross-piece at right angles to it and parallel with each other. The arms of the frame C slide in eyes d d' d'' d''' , that depend from the beams B B, and each carries a collar, C' , and a spring, C'' , and the collars C' are connected by a pivoted cross-piece, C^3 , that carries a counterbalanced lever, D. This lever D has a rounded flange, D', on its front end, that is adapted for engagement with a recess, a'' , in the under side of the shank A' of the draw-head, and to connect the frame C with it to set the device for automatic coupling, and to hold the end D' of lever D up in the recess a'' , I provide a small U-shaped sliding frame, E, the arms e e' of which I pass through eyes e' , interposing a spring between the eyes e' on each arm. The under side of the cross-piece

of frame E is beveled, or is made slanting, to permit the head D' to wedge it out of the way as it is forced up into the recess a'' by one of the bell-crank levers F. The levers F are fulcrumed to the under side of the car-bed, each in a pair of brackets, f f' , and each has an arm, F' , that extends up and out in position to be easily reached from the side of the car; and to place one of these arms F' and its lever under control of a person standing on the platform or top of the car, I pivot a small lever, g , to the front end of the car on one side of the draw-head, as shown in the drawings, Fig. 1, and just inside of one of the arms F' , with its head, g' in position to strike the upper end of lever F, when its lower end, g^2 , is drawn upon by a rope or chain, G, that extends up to the top of the car.

H is a lug that is beveled on its under side, and forms part of the frame C, and this lug is adapted to engage with the lower cross-piece of a pin-yoke, L, that slides up and down in eyes l l' , secured to the front of the car-frame, and is guided by a bolt, M, that is secured to the front of the frame by small brackets and passes loosely down through a lug, l' , on lower cross-piece, l^2 , of the yoke. The vertical arms of the yoke carry loops m to receive the inner ends of levers N, by which the yoke L is raised to uncouple the cars.

O are arms that extend out from the upper cross-piece of yoke L over the draw-head, and between these arms I place a plate, O', grooved on each side to receive them. This plate O' is adapted to slide freely on these arms, and a pin, o , projecting up through it from the draw-head, serves as a guide for it, and to connect it with the draw-head, so that its pin-holes will always be directly over corresponding pin-holes in the draw-head. The pin o is shouldered at about its middle, and projects down through an opening in the draw-head, which is enlarged at top and bottom to permit the draw-head to slightly vibrate about a horizontal center without cramping said pin.

R is a removable coupling-pin, that passes through the plate O' just in front of the pin o and down through link-chamber S on one side of the draw-head; and R' is a central pin, that passes down through the central link-chamber,

S' , while R^2 is the pin that holds a link in chamber S^2 for coupling with an opposing car. s is a pin that passes through the draw-head in the rear of chamber S^2 , and has a lip, s' , that, resting on the inner end of the link, guides its other end into the link-chamber of an approaching car. To prevent the withdrawal of pin s , I perforate it near its lower end and force a pin, s^2 , into it.

10 Operation: To uncouple the cars I press upon the outer end of one of the levers N , and thereby lift the pin-yoke and the coupling-pins, and as the yoke rises its lower cross-bar, l^2 , wedges back the lug H on frame C until it rises above it, when the lug shoots forward in position to support the yoke when the lever N releases it. Now, no amount of jarring will cause the yoke to drop the pins; but to set the coupling for automatic action it is only necessary to depress an arm, F' , until the end of its lever F throws the flanged end D' of the lever D up into the recess a'' past the head of the sliding frame E , which yields to permit this action, after which it is drawn back by the springs on arms e beneath the head D' to hold it up in the recess a'' . Now, the draw-head and the frame C are connected by the lever D , and therefore when the draw-head A is struck by a draw-head on an approaching car, as it 25 yields it carries the frame C back with it until the lug H is carried from beneath the bar l^2 of the yoke, and the latter falls with its coupling-

pins and couples the cars; and to prevent the yoke from injuring the loops m , I provide brackets o' , (such as shown in Fig. 1,) that catch 35 the yoke before it falls far enough for the loops to strike the eyes $l l$.

What I claim as new, and desire to secure by Letters Patent, is—

1. The lever F , in combination with levers g and counterbalanced lever D , substantially as set forth.

2. In combination with the draw-head, the shank of which is recessed at a'' , the U -frame E , having beveled cross-piece, the balanced 45 lever D , and a setting-lever, as set forth.

3. The sliding pin-yoke, in combination with levers for lifting it and brackets O' for limiting its downward movement, as set forth.

4. The combination of the yoke and coupling and guide pins with the draw-head having flared pin-holes, as set forth.

5. The combination of frame E , balanced lever D , levers g and F , and cord or chain G with the pin-yoke and frame C , the latter carrying a lug, H , as set forth.

In testimony that I claim the foregoing I have hereunto set my hand on this 11th day of August, 1882, in the presence of two witnesses.

FREDERICK W. BROOKS.
